UNITED STATES PATENT OFFICE

2,233,051

DIAPHRAGM FOR RAILWAY CARS

Larry A. Hansen, Philadelphia, Pa., assignor to
 The Pennsylvania Railroad Company, Philadelphia, Pa., a corporation of Pennsylvania

Application August 2, 1940, Serial No. 349,442

4 Claims. (CL 105—21)

This invention has reference to improvements in railway car end diaphragms and, more particularly, to the species including an inner face plate with spacially related and hinged flanking 5 or outer face plates, with associated means normally influencing such diaphragms on adjoining car ends into mutual engagement.

Diaphragm structures of the above specified type while measurably successful do not maintain a definite tension on the outer diaphragm intervening the adjoining car end side walls, more especially when such diaphragms are located for streamlining the cars; and, the primary object of this invention is the provision 15 of a novel means for outwardly influencing the end face plate wing portions so as to maintain the outer diaphragm members under tension at all times, irrespective of variations in the running of connected cars when "rounding" or traversing railroad curves in either direction.

Another object is to provide means of the above typified species which operates under all normal service conditions to keep the inner and outer diaphragm face plates outwardly influenced with respect to the adjoining car end, so that when two cars correspondingly equipped 25 are coupled together the respective face plates are maintained in operative registration.

Other objects, with ancillary advantages, will 30 become apparent from the following detailed description of a preferred embodiment thereof, as shown by the accompanying sheet of illustrative drawings, wherein like reference characters designate corresponding parts in the respective views; while the concluding claims more particularly define the features of novelty over the prior art.

In the drawing:

Fig. 1 is an end elevation of a railway car body 40 including the improvements of this invention; and,

Fig. 2 is a cross-section, taken substantially as indicated by the arrows II—II in Fig. 1.

In describing the form of this invention exemplified on the drawing herewith, specific terms will be employed for the sake of clarity, but it is to be understood the scope of said invention is not thereby limited; each such term being intended to embrace all equivalents which perform the same function for an analogous purpose.

Referring to the drawing, a railway car body end is comprehensively designated by the numeral 3, the same including conventional vestibule and corner posts 4, 5, respectively; while 6 is the bumper sill, and 7, 8 the inner and outer dia-

phragms, with an associated face plate 9, and wing plates 10 pivoted to said face plate by hinges 11 in accordance with known practice. The outer diaphragm 8 is connected along one vertical edge by suitable means 12 to the car corner post 5 and complementary means 13 to the outer edge portion of the registering wing plate 10; said means preferably being of the species forming the subject matter of a companion application Serial No. 349,443, and filed concurrently here- 10 with.

In order that the respective wing plates 10 shall be normally influenced outwardly so as to exert a constant tension on the outer diaphragm 8, use is preferably made of upper and lower flat-springy and outwardly-tapering leaf members 14, having their inner or larger and approximately rectangular ends 15 permanently fixed by securing means 16, to the outer vertical flanges 17 of the respective vestibule posts 4. Each of the 20 narrower ends of the members 14 is retroverted to provide a hinge loop 18 for passage of a pivot pin 19, whereby said loop is connected between the apertured ears 20 of a shoe 21 afforded slideable movement in the stiffening structure 22 of the respective wing plates 10. Incidentally, it is to be noted that in Fig. 2 the respective diaphragms 7, 8 and associated face plates 9, 10 are shown in the normal or "uncoupled" position, while the reference 23 designates the extent of 25 inward collapse towards the car body end 3 when adjoining car ends are coupled together.

From the foregoing the merits and advantages inhering to this invention will be clearly apparent to those conversant with car vestibule and diaphragm constructions, but it is herein desired to emphasize the fact that by using opposed leaf members 14 proximate the upper and lower portions of the face plate 9 and hinged wings 10, that both of said parts of one car are firmly 40 braced in mutual registration with the corresponding parts of a coupled car.

Having thus described my invention, I claim:

1. In diaphragm connections for the adjoining ends of mobile cars including spaced inner and outer flexible diaphragm members; the combination of a face plate, parallel to and longitudinally spaced relative to the adjacent car end wall, and having flanking pivotal wings providing longitudinally spaced extensions of the 50 peripheral contour of the car; and laterally-directed springy leaf-elements intermediate the vestibule posts and the wings for urging the latter away from the car end wall, whereby said wings are constrained to exert constant tension 55.

on the outer diaphragm members with concurrent outward influencing of the face plate.

2. In diaphragm connections for the adjoining ends of railway cars including spaced inner and outer flexible sheet diaphragms; the combination of a face plate sustained by the vestibule posts parallel to and longitudinally in advance of the car end wall, flanking wings vertically-hinged to said face plate; means connecting the outer flexible diaphragms between the car end corner posts and the outer vertical edges of the face plate wings; and opposed laterally-directed springy leaf-elements having their inner ends rigidly secured to the vestibule posts with their

outer ends connected to shoes slidably carried by the respective wings for urging the latter away from the car end.

3. The combination of claim 2 wherein each leaf-element consists of an outwardly-tapering member with the wider end square, and the smaller end retroverted to define a pivot-loop.

4. The combination of claim 2, wherein the outer end of each leaf-member is looped and hingedly connected to a laterally slidable shoe, and said shoe is afforded slidable movement in the stiffening structure of the associated face plate wing.

LARRY A. HANSEN.
